UNITED STATES PATENT OFFICE

JAMES S. REID, OF SHAKER HEIGHTS, OHIO, ASSIGNOR TO THE REID PRODUCTS COMPANY, OF CLEVELAND, OHIO, A CORPORATION OF OHIO

GLASS RUN CHANNEL

Application filed March 30, 1931. Serial No. 526,403.

The invention disclosed in this application relates to glass run channels for slidable automobile windows and the like.

The trend of the industry in glass run channels is toward providing finishing strips for the exposed and outer edges of the channel side walls to thereby do away with the unsightly appearance of said edges.

In view of the foregoing, this invention relates to a glass run channel including the usual substantially U-shaped spring-like metal core having the usual soft covering or cushioning material and provided with finishing strips of stainless steel or the like at the outer edges of its side walls, said finishing strips projecting outwardly and terminating in ornamental beads to more or less conceal the glass-engaging outer edges of the channel side walls and to give proper finish to the channel.

Two embodiments of the invention are fully set forth in the following description, drawing and claims.

Referring to the drawing, Fig. 1 is a perspective view of a short piece of finished channel illustrating one embodiment of the present invention; Fig. 2 is a side view of the stripped metal core of the channel of Fig. 1; Fig. 3 is a view similar to Fig. 1 and illustrating another embodiment of the present invention, and Fig. 4 is a side view of the stripped metal core of the channel of Fig. 3.

In each of the arrangements or embodiments shown, the channel core is made of spring-like material, such as spring steel, bent into substantially U-shape to provide a base 1 and a pair of side walls bent inwardly toward each other, as shown, to yieldingly but firmly press against the glass which the channel is to receive. At the outer edge of each of the channel core side walls there is a bead formed by folding the metal back, as at 3. According to one embodiment of the present invention, the outer portions 4, including the beads 3 thereof, of the channel core side walls may be made of separate metal strips as shown in Figs. 1 and 2, having their inner edges welded or otherwise suitably secured as at 5 to the inner surfaces of the outer edges of the inner flange portions

2 of the channel core side walls. Welded or otherwise suitably secured at substantially these same points 5, but to the outer surfaces of the inner flange portions 2 of the channel core side walls are the inner edges of curved 55 finishing strips 6 of stainless steel or the like and each provided at its outer edge with a rolled portion 7 forming an ornamental finishing bead. In this arrangement, as shown in Figs. 1 and 3, the three parts of each core 60 side wall, i. e., the outer strip portion 4, the inner flange portion 2, and the finishing strip 6 may be all welded together at one operation. When the core parts 2, 4 and the finishing strips 6 are assembled or secured 65 together in this manner, the metal core parts 1, 2 and 4 may be provided with the usual covering or cushioning material, comprising inner layers 8 of rubber and outer layers 9 of felt, and as shown, the covering or cushioning material for the inner flange portions 2 of the core side walls terminates at the welding points 5. Also as shown, the covering or cushioning material, indicated at 10, for the outer side wall portions 4, with their 70 beads 3, more or less completely envelop said portions, which are, of course, glass-engaging 75 portions.

In order to prevent the covering or cushioning material from pulling off of the core side wall portions 2 and 4 adjacent the exposed portions 5, where the welding takes place, I prefer to provide said core portions 2 and 4, adjacent said welding points, with longitudinal groups of perforations 11 and 12, perforations 11 being in the inner side wall portions 2 and perforations 12 being in the outer side wall portions 4, so that the rubber 8 of the covering or cushioning material may pass through these openings and form an interlocking bond or securing means between the outer and inner rubber layers, all as clearly shown in the accompanying drawing and as will be readily understood.

In the embodiment or arrangement shown 95 in Figs. 3 and 4, the core side walls are of integral construction, as shown, and the metal finishing strips 6 are welded or otherwise suitably secured at 5 to the outside surfaces of the core side walls intermediate the inner 100

and outer edges thereof. The perforations 11 and 12 are used in this construction, as well as in the construction of Figs. 1 and 2, to hold the covering or cushioning material 5 in place on each side of the bare points where the welding operation occurs.

In use, the glass slides between the covered outer edges of the channel side walls and the finishing strips 6 serve to hide to 10 some extent at least said outer edges, thereby presenting a slightly finish at these points, all as will be readily understood.

Having described my invention, I claim:

1. A glass run channel, comprising a generally U-shaped channel structure having a base and a pair of side walls, said side walls having their outer edges turned inwardly toward each other for yielding glass engaging purposes, and a pair of finishing strips, 20 one for each side wall, each of said finishing strips having its inner edge secured to the outer surface of one of said side walls intermediate the inner and outer edges thereof.

2. A glass run channel, comprising a generally U-shaped channel structure having a base and a pair of side walls, said side walls having their outer edges turned inwardly toward each other for yielding glass engaging purposes, and a pair of finishing strips, 30 one for each side wall, each of said finishing strips having its inner edge secured to the outer surface of one of said side walls intermediate the inner and outer edges thereof, 35 the outer edges of said finishing strips being spaced from the glass engaging outer edges of said channel structure.

3. A glass run channel, comprising a generally U-shaped channel structure having a base and a pair of side walls, said side walls having their outer edges turned inwardly toward each other for yielding glass engaging purposes, and a pair of finishing strips, one 40 for each side wall, each of said finishing strips having its inner edge secured to the outer surface of one of said side walls intermediate the inner and outer edges thereof, the outer edges of said finishing strips being rolled outwardly and being spaced from the 50 glass engaging outer edges of said channel structure.

4. A glass run channel, comprising a generally U-shaped metal channel member having a base and a pair of side flanges, a pair 55 of resilient metal strips, one for each side flange, each of said resilient metal strips having its inner edge secured to the outer edge of one of said side flanges, the outer edges of said resilient strips being bent inwardly 60 toward each other and being adapted to yieldingly engage a glass inserted therebetween, and a pair of finishing strips, one for each side flange, each of said finishing strips having its inner edge secured to the outer edge 65 of one of said side flanges.

5. A glass run channel, comprising a generally U-shaped metal channel member having a base and a pair of side flanges, a pair of resilient metal strips, one for each side flange, each of said resilient metal strips having its inner edge secured to the outer edge of one of said side flanges, the outer edges of said resilient strips being bent inwardly toward each other and being adapted to yieldingly engage a glass inserted therebetween, 70 and a pair of finishing strips, one for each side flange, each of said finishing strips having its inner edge secured to the outer edge of one of said side flanges, the outer edge of each of said finishing strips being spaced 80 from the outer edge of the adjacent glass engaging resilient strip.

In testimony whereof I hereby affix my signature.
